UNITED STATES PATENT OFFICE.

JOSHUA B. HALE, OF PROVIDENCE, RHODE ISLAND, ASSIGNOR TO TEXTILE ENGINEERING COMPANY, OF PROVIDENCE, RHODE ISLAND, A CORPORATION OF RHODE ISLAND.

BRAIDING MACHINE.

Application filed April 25, 1923. Serial No. 634,473.

To all whom it may concern:

Be it known that I, JOSHUA B. HALE, a citizen of the United States, and a resident of Providence, in the county of Providence and State of Rhode Island, have invented an Improvement in Braiding Machines, of which the following description, in connection with the accompanying drawings, is a specification, like characters on the drawings representing like parts.

This invention relates to braiding machines. In order that the principle of the invention may be readily understood, I have disclosed a single embodiment thereof in the accompanying drawings, wherein—

Fig. 1 is a plan view of the body structure showing the quoits in position;

Fig. 2 is a transverse section on the line 2—2 of Fig. 1;

Fig. 3 is a transverse section upon the dotted line 3—3 of Fig. 1;

Fig. 4 is a plan view upon an enlarged scale of a portion only of the structure shown in Fig. 1 and representing also certain of the carriers;

Figs. 5 and 6 are side elevations of a left and a right carrier respectively;

Figs. 7 and 8 are vertical transverse sections upon the lines 7—7 and 6—6 respectively of Fig. 4; and

Fig. 9 is a perspective view of carrier guiding or directing means constituting an important feature of my invention.

The body structure 1 may be of any suitable type or character. It may for example be of the unitary type disclosed in my co-pending application Serial No. 512,317, filed November 2, 1921, and is so shown. It is clearly to be understood, however, that my invention is not limited in this respect. I have herein shown said body structure as of the type disclosed in said co-pending application and have represented it as provided with an inner wall 2 and an outer wall 3 so shaped as to provide a communicating series of open top depressions, wells or recesses 4 for the reception of the quoits 5 and wherethrough the carriers 6, 7 may circulate under the guidance of said walls and quoits.

Each of the quoits 5 is notched at proper intervals as indicated at 8 for the reception of the stems 9 of the carriers 6, 7. Each quoit 5 is mounted for rotation upon its

own axis in its own depression, well or recess, and for that purpose is provided with a gear 10. Each of the walls 2, 3 is curved in a series of intersecting segments so as to provide projecting angles in pairs directed toward each other, the space between each pair of angles constituting the communicating opening between adjacent depressions, wells or recesses. The distance between each pair of angles is substantially the length of a carrier 6 or 7 and is desirably of almost exactly that length. Each of said walls 2, 3 is vertical or straight viewed perpendicularly. Each of the quoits 5 has an outer cylindrical surface 11 which at some point between the upper and lower extremities of said cylindrical surface is desirably provided with an annular flange 12 wherein the notches 8 occur. Thus it will be apparent that the cylindrical surface 11 of each quoit provides a vertical surface sufficiently spaced from the adjacent portion of the face 2 to provide a groove, channel or raceway for the reception of the carriers 6, 7. It will thus be evident that the groove, channel or raceway at its inner portion exists between the vertical face 2 and the vertical surface 11 of the quoits 5, and at its outer portion exists between said vertical surfaces 11 of said quoits 5 and the vertical wall 3. Said groove, channel or raceway is thus parallel walled, the flanges 12 being employed or not as desired, and is uniform in structure or character from top to bottom.

At each of the angles of the inner wall 2 and at each of the angles of the outer wall 3, I provide means, preferably fixed, for guiding or directing the carriers in their sinuous paths in the groove, channel or raceway. Said means may be integral with the body structure 1, or of some portion of said body structure if the latter be made in more than one piece, or said means may be formed of one or more pieces and secured, preferably fixedly, in position at said angles. Said latter structure is preferred, and is here shown. The structure is preferably such as to cooperate with distinctive carriers and for that reason, I desirably and herein provide two types of carriers, there being one or more carriers of each type. Such carriers I term right and left carriers, the right carrier being rep-

resented in Fig. 6, and the left carrier in Fig. 5. Each of said carriers has its upper portion 13 of lenticular shape and all the carriers are desirably identical 5 in this respect. The lateral walls of said portions 13 are received between the wall 2 or the wall 3, and the lateral, cylindrical surface 11 of the quoits 5 and the stems or reduced portions 9 are received in the 10 notches 8 of the quoits. Upon some suitable portion of at least one of the carriers 6, 7, I provide a formation constituting a clearance for the fixed guiding points not functioning in guiding the particular carrier 15 on which clearance is provided. In the disclosed embodiment of the invention, I provide a groove 16 but the position of the groove may obviously be varied in accordance with the position of the guiding means. 20 For example, such groove 16 might be above or below the horizontal groove provided for the reception of the flange 12 of the quoit.

Referring merely to the disclosed embodiment of the invention, I have provided below the reduced portions 9, the part 14 upon the right carrier 6 and the portion 15 upon the left carrier 7. Said portions 14, 15 are herein in part of the same size and form as the portions 13, but the portion 14 has an 30 annular groove 16 intermediate the upper and lower surfaces of said portion 14 and the portion 15 is in this instance devoid of such a groove and desirably terminates at the bottom, horizontal surface 17. The exact position of said groove 16 may be varied and below it is provided the curved surface 16'. The groove 16 constitutes a clearance for the fixed guiding element not used in guiding the particular carriers having such 35 groove. Referring to the carrier 7, which is shortened, so that its bottom surface is above the level of the lower fixed guiding elements, it is pointed out that it is not necessary that clearance be made to allow 40 the carrier to pass over such guiding elements.

The guiding or directing means to which I have referred as positioned at the angles of the walls 2, 3 cooperate with the surface 50 16' of the carrier 6, and the unbroken wall 15 of the carrier 7. Desirably for this purpose I provide the following construction, to which my invention is not limited but which I disclose as the preferred embodiment thereof.

At each of said angles I position in suitable recesses for that purpose two plates or pieces 18, 19 shown most clearly in Fig. 9 and which as already stated may be integral 60 with each other or be formed in any suitable way. Assuming for purposes of description that at each angle I provide two plates or pieces 18, 19, I desirably secure each of them in position by a vertical pin 20 as most clearly shown in Figs. 7 and 8. Said pieces

17, 18 are pointed as clearly shown in Figs. 1, 4 and 9, and are provided with curved edges 21, 22, 23, 24, the curvature of said walls 21, 22 corresponding to the curvature of the surface 15, and the curvature of the 70 edges 23, 24 corresponding to the curvature of the surface 16' below the groove 16. Said plates or pieces 18, 19 overlap as indicated most clearly in Fig. 9, and the structure is such and the distance apart of each 75 pair of such plates or pieces 18, 19 is such as clearly represented in Fig. 4 that each carrier is for a brief instant of time supported at both its leading and trailing ends by a pair of said plates or members. Such 80 condition is shown at the position B of the right hand carrier 6, the said carrier being shown at A, B, C in three different positions. The left hand carrier 7 is shown in Fig. 4 in one position. 85

It is evident that as each carrier is supported for a brief instant at both its leading and trailing ends, and as the guiding or directing means is rigid, no lost motion occurs and there is no possibility of any 90 carrier being directed into a wrong portion of the groove.

I am aware that it has heretofore been proposed to form two carrier raceways in different horizontal planes, one overlying or 95 existing above the other, and at the angles of said raceways the carriers have been directed into the proper portion of the groove by reason of the different widths of the two raceways. My invention is radically differentiated from such a construction. I employ but a single raceway, and that raceway is of the same size or lateral dimensions from its bottom to its top, as, for the purposes of this statement, the flange 100 12 may be disregarded as it may or may not be employed. At the inner and outer angles of such single raceway, I provide the guiding or directing means, one type or embodiment of which I have disclosed, and I provide 105 right and left braiding carriers, all of which are desirably identical in structure, excepting for the groove 16, as the carrier 7 may or may not be shortened at its base 17, as 110 desired. 115

It will be observed that I have provided fixed guiding elements, and referring to the structure shown in Fig. 9, it is noted that the guides 18, 19 are superimposed, although they need not necessarily be exactly together or in contact. Such guiding elements project into the raceway in angular relation to each other. 120

Having thus described one illustrative embodiment of my invention, I desire it to 125 be understood that although specific terms are employed, they are used in a generic and descriptive sense and not for purposes of limitation, the scope of the invention being set forth in the following claims. 130

Claims—

1. A braiding machine having a body with communicating recesses and a series of rotatable quoits mounted in said recesses, there being a raceway of uniform character from top to bottom provided by and between the adjacent surfaces of said quoits and recesses, said raceway having angular portions where the recesses communicate, and fixed means on said angular portions to guide or direct the carriers into the proper portion of said raceway. 5
2. A braiding machine having a body provided with a series of communicating open topped recesses; a series of rotatable quoits mounted in said recesses, there being a raceway of uniform character from top to bottom provided by and between the adjacent upright series of said quoits and recesses, said raceway having angular portions where the adjacent recesses communicate, and fixed means at said angular portions to guide or direct the carriers into the proper portion of said raceway. 15
3. A braiding machine having a body with communicating recesses and a series of rotatable quoits mounted in said recesses, there being a raceway provided by and between the adjacent surfaces of said quoits and recesses, said raceway having angular portions where the recesses communicate, and fixed means on said angular portions to guide or direct the carriers into the proper portion of said raceway. 25
4. A braiding machine body structure having a raceway of uniform character, said raceway presenting a sinuous path with angles arranged in pairs spaced apart substantially the length of the carriers and fixed guiding or directing means at said angles. 35
5. A braiding machine having a body wherein are provided a series of communicating recesses, a series of quoits rotatably mounted in said recesses and spaced from the walls of the latter to provide a raceway having opposed angular portions, said raceway being of uniform character from top to bottom, and fixed guiding or directing means at said opposed angular portions. 45
6. A braiding machine having a body wherein are provided a series of communicating recesses, a series of quoits rotatably mounted in said recesses and spaced from the walls of the latter to provide a raceway having opposed angular portions, right and left carriers positioned in said raceway and fixed guiding or directing means at said opposed angular portions. 55
7. A braiding machine having a body wherein are provided a series of communicating recesses, a series of quoits rotatably mounted in said recesses and spaced from the walls of the latter to provide a raceway having opposed angular portions, said raceway being of uniform character from top 65
- to bottom; a series of right and left carriers mounted in said raceway, and guiding or directing means for said carriers positioned at said opposed angular portions. 70
8. A braiding machine having a body wherein are provided a series of communicating recesses, a series of quoits rotatably mounted in said recesses and spaced from the walls of the latter to provide a raceway having opposed angular portions, said raceway being of uniform character from top to bottom, a series of right and left carriers positioned in said raceway and fixed guiding or directing means for the carriers at said angular portions. 75
9. A braiding machine having a body wherein are provided a series of communicating recesses, a series of quoits rotatably mounted in said recesses and spaced from the walls of the latter to provide a raceway having opposed angular portions, right and left carriers positioned in said raceway, and having selecting formations in different horizontal planes, and guiding means at said angular portions respectively to engage said contrasting formations. 80
10. A braiding machine having a body wherein are provided a series of communicating recesses, a series of quoits rotatably mounted in said recesses and spaced from the walls of the latter to provide a raceway having opposed angular portions, a series of right and left carriers in said raceway and having selecting formations in different horizontal planes, and fixed overlapping guiding or directing means at said angular portions to engage respectively the said selecting formation of the carriers. 85
11. A braiding machine having a body wherein are provided a series of communicating recesses, a series of quoits rotatably mounted in said recesses and spaced from the walls of the latter to provide a raceway having opposed angular portions, and fixed guiding means at said angular portions, the members of an opposed pair of said guiding or directing means being spaced apart substantially the exact length of a carrier. 95
12. A braiding machine having a body wherein are provided a series of communicating recesses, a series of quoits rotatably mounted in said recesses and spaced from the walls of the latter to provide a raceway having opposed angular portions, and fixed guiding or directing means at said angular portions and consisting of two pointed plates slightly overlapping to present selecting guiding means for the carriers. 100
13. A braiding machine having a body wherein are provided a series of communicating recesses, a series of quoits rotatably mounted in said recesses and spaced from the walls of the latter to provide a race- 105
- 110
- 115
- 120
- 125
- 130

way having opposed angular portions, fixed guiding or directing means at said angular portions and consisting of two pointed plates slightly overlapping to present selecting guiding means for the carriers, and two sets of carriers having contrasting forms to engage the edges of said two plates of each guiding or directing means.

14. A braiding machine having a body wherein are provided a series of communicating recesses, a series of quoits rotatably mounted in said recesses and spaced from the walls of the latter to provide a raceway having opposed angular portions, and guiding and directing means at each angular portion consisting of two plates fixed in position and slightly laterally overlapping, each plate having a point and two faces curved away from said point on the radius 20 of a portion of the carrier guided thereby.

15. A braiding machine having a body wherein are provided a series of communicating recesses, a series of quoits rotatably mounted in said recesses and spaced from the walls of the latter to provide a raceway having opposed angular portions, the raceway thus having two parallel walls, one of which is constituted by the series of quoits, and fixed guiding or directing means at 30 said opposed angular portions.

16. A braiding machine having a body

wherein are provided a series of communicating recesses, a series of quoits rotatably mounted in said recesses and spaced from the walls of the latter to provide a raceway having opposed angular portions, fixed angular directing means at said opposed angular portions, said directing means having selecting parts, and two series of carriers which are guided in said raceway and are guided or directed at said opposed angular portions by the selecting parts of said guiding or directing means.

17. A braiding machine having a body provided with a series of communicating open topped recesses; a series of rotatable quoits mounted in said recesses, there being a raceway of uniform character from top to bottom provided by and between the adjacent upright series of said quoits and recesses, said raceway having angular portions where the adjacent recesses communicate, fixed means at said angular portions to guide or direct the carriers into the proper portion of said raceway, and a series of right and left carriers in said raceway, said fixed means respectively having selecting parts to cooperate respectively with said right and left carriers.

In testimony whereof, I have signed my name to this specification.

JOSHUA B. HALE.
